UNITED STATES PATENT OFFICE

159,643

COMBINED CHILD'S DISH AND CUP

Gerald R. Kelly, Mystic, Iowa, and Donald D. Davies, Minneapolis, Minn., assignors to Ace Plastic Products, Inc., Fergus Falls, Minn., a corporation of Minnesota

Application May 11, 1949, Serial No. 2,571

Term of patent 14 years

(Cl. D44—15)

To all whom it may concern:

Be it known, that we, Gerald R. Kelly and Donald D. Davies, citizens of the United States, residing at Mystic, Iowa and, Golden Valley, Minneapolis, Hennepin County, Minnesota, respectively, have invented a new, original, and ornamental Design for a combined Child's Dish and Cup, of which the following is a specification, reference being had to the accompanying drawings forming a part thereof.

Fig. 1 is a top perspective view of a combined child's dish and cup showing our new design with the cup raised above the dish;

Fig. 2 is a side elevational view; and

Fig. 3 is a front elevational view of the cup only.

We claim:

The ornamental design for a combined child's dish and cup, substantially as shown.

GERALD R. KELLY.
DONALD D. DAVIES.
